United States Patent Office

Des. 216,460
Patented Jan. 13, 1970

216,460

BOTTLE

John Gibson, Rockville Center, N.Y., assignor to The Gillette Company, Boston, Mass., a corporation of Delaware

Filed Feb. 28, 1969, Ser. No. 15,963

Term of patent 14 years

Int. Cl. D9—01

U.S. Cl. D9—63

FIG. 4

FIG. 5

FIG. 3

FIG. 1

FIG. 2

FIG. 1 is a view in side elevation of a bottle showing my new design;

FIG. 2 is a view in elevation taken from the left hand side of FIG. 1;

FIG. 3 is a top plan view;

FIG. 4 is a view in section taken along line 4—4 of FIG. 1; and

FIG. 5 is a view in section taken along line 5—5 of FIG. 1.

I claim:

The ornamental design for a bottle, as shown.
